DRIFTING CONTROL VALVE

Lloyd B. Jones, Hollidaysburg, Pa.

Application April 30, 1942, Serial No. 441,098

16 Claims. (Cl. 121—134)

This invention has general reference to means for controlling the admission and exhaust of motive fluid to and from the cylinders of reciprocating engines; and more particularly relates to locomotive fluid distribution systems wherein individual poppet valves serve for admitting and exhausting steam to and from each cylinder, although the instant improvements are not necessarily restricted to such systems.

One of the inherent advantages of the subdivision of function to individual poppet valves in the fluid distribution systems of locomotives, more particularly, is the opportunity afforded for holding the exhaust poppet valve closed while "drifting" and thereby prevent in-drawing of smoke, gases and cinders from the smoke-box, through the exhaust space into the engine cylinders.

In order that full benefit may be had of the noted advantage it is essential that the exhaust poppet valve be held closed, while circulation of a sufficiency of the motive medium should take place, through the engine cylinders, to overcome frictional resistance of the relatively moving parts while "drifting."

The primary aim of this invention is to furnish a drifting control device which ensures positive attainment of the advantages recited in the preceding paragraph.

Another aim of this invention is the provision of an automatic "drifting" control device including a differential piston having a directly-associated double-seating release valve, preferably for operation in combination with the fluid-actuated poppet valve of reciprocating engines.

A further aim of this invention is to provide a "drifting" control valve for application to steam locomotives which is comparatively simple in construction, automatic in action, and comprises but few parts.

For the purpose of illustrating this invention, there is shown by the accompanying three sheets of drawings a typical embodiment which is, at present, considered to be preferable, since such will give in practice satisfactory and reliable results; although it is to be understood that the combination of instrumentalities which said embodiment includes may be otherwise arranged and organized with corresponding advantages, hence the instant disclosure is not to be construed as limitative other than reasonable interpretation of the concluding claims requires.

In the drawings:

Fig. 1 is a fragmentary sectional view of one end of an engine cylinder having an arrangement

of admission and exhaust poppet valves, substantially in accordance with applicant's prior Patent No. 2,260,458, dated October 28, 1941, on "Locomotive steam distribution system," and also including the drifting control device of the instant invention, as an auxiliary, with the associated connections to the engine cylinder admission and exhaust poppet valves.

Fig. 2 is a longitudinal section through the drifting control device of Fig. 1, drawn to a larger scale for better illustration of structural details, and with the movable parts in the position they occupy under normal running conditions of the locomotive.

Fig. 3 is a similar section to the preceding figure, but showing the movable parts as located when the locomotive is "drifting."

Fig. 4 is a transverse section on the arrowed plane IV—IV of Fig. 2.

Fig. 5 is a similar section on the plane V—V of Fig. 2; and,

Fig. 6 is a cross-section on the staggered plane VI—VI in Fig. 3.

In describing the form of this invention exemplified by the above captioned drawings, specific terms will be employed for the sake of clarity, but it is to be understood the scope of said invention is not thereby limited, each such term being intended to embrace all reasonable equivalents which perform the same function for an analogous purpose.

Referring more in detail to Fig. 1 of the drawings, the reference character 9 designates a fragmentary portion of a locomotive engine cylinder having an associated steam chest 10, and exhaust passage 11. The steam chest 10 is provided with admission poppet valves 12 having a companion pilot-valve 13, while the passage 11 is similarly equipped with an exhaust poppet valve 14 and allied pilot-valve 15; said pilot-valves 13, 15 being shiftable by push rods 16, 17, respectively, under actuation of a master controlling cam 18: all substantially in accordance with the disclosure of the patent hereinbefore referred to, and they are merely referred to by way of affording suitable background in explaining the illustrated device of the present invention, which is comprehensively identified by the numeral 19, the same being well adapted for attainment of the objects specified.

The drifting control valve or device 19, as best shown by Figs. 2—6 inclusive, comprises two main, or a lower and an upper, hollow casing components 20, 21 respectively; the former 20 of which embodies a supporting flange 22, see Fig. 6 only,

whereby said valve is attachable to any rigid part of the locomotive, not shown; while said casing components 20, 21 are preferably connected together in axial alignment by a screw-thread joint 23.

The casing component 20 is closed-in by a bottom wall 24 having a screw-threaded aperture 25 for attachment of one end of a pipe connection 26, correspondingly secured at 27 into the exhaust passage 11, see Fig. 1. In addition the casing component 20 includes diametrically-opposed apertures 28 for threaded connection of pipes 29, 30, the former 29 leading to the admission poppet valves 12 at the front end of the cylinder 9, and the latter 30 similarly communicating with admission poppet valves—not shown—at the back end of said cylinder, as readily understood by those conversant with the art; while the bore of the casing component 20 is, preferably, fitted with a friction reducing liner 31.

Secured by threaded-connection 32, to the upper end of the valve component 21, is a polygonally-shaped cap 33 affording axial attachment, by a nipple 34, for a union-elbow 35, in turn having pipe connection 36 into the steam chest 10, at any desirable point, not indicated, so that when the locomotive throttle is opened, pressure from said chest also enters the control device 19, as well as the poppet valves 12, for a purpose later explained.

Within the drifting control device 19 and movable in the liner 31 of the casing component 20 is a differential-piston 37, preferably of stainless steel to eliminate sticking due to corrosion; while a double-seating release-valve 38 operates in the casing component 21, said release-valve having movement imparted thereto by the piston 37, through the medium of a central stem 39 slidable in an axial bore 40, of a transverse wall 41 between the ends of said casing component 21. The stem 39, it is to be noted, is of a length for abutment by the inner end of a hollow section 42 of the piston 37, in the manner hereinafter set forth. Attention is also directed to the fact that the piston 37 has the solid portion 43, beyond the hollow section 42, slightly reduced to define a bevel 44 for engagement with a complementary seat, or flare, 45 in the bore 46 of the liner 31; while a proximately-related circumferential groove 47 has an inclined continuously open drain duct 48 connecting into an axial bore 49 of the solid portion 43; said duct serving to permit any condensation collecting in the groove 47, when the piston valve 37 is seated as shown in Fig. 2, to drain into the exhaust 25. In addition the solid portion 43 is provided with a surrounding recess 50; while the outer surface of the hollow section 42 is appropriately grooved at 51, to reduce friction. The differential piston 37 it is to be particularly remarked embodies a minor differential area which is made by the difference between bevel seats 44 and 45 and the external diameter of piston 37. This differential area is comparatively small but is sufficient to lift the piston 37 when the steam chest pressure acting on the top of it disappears due to closing of the locomotive throttle; which said differential also includes that portion of the piston 37 of reduced diameter intermediate the bevel 44 and the lower part of said piston including the grooves 51, plus the circumferential groove 47, see Fig. 3 to best advantage.

Referring again to the valve component 21 which is, preferably, of polygonal formation ex-

cepting for the screw-threaded end that receives the cap 33; the same embodies a lateral orificed branch 52 for attachment of one end of a pipe 53, connecting into the cylinder exhaust passage 11 at 54, Fig. 1; while it is to be observed that the central portion of the transverse wall 41 is thickened and suitably shaped to define a bevel-seat 55 for the complementally-flared lower end 56 of the release-valve 38; whereas an annular series of apertures 57 are provided through said central portion. It is to be further remarked, the upper portion of the component 21 is conveniently drilled, before finishing interiorly, to provide a series of equally spaced longitudinal grooves or flutes 58 terminating at the inner ends proximate a beveled shoulder 59, preferably, outwards relative to the exhaust connection 52 and wall 41. It will also be apparent that when the valve 38 is in the up position of Fig. 3 it would be sealed were the flutes 58 not provided; while said flutes are necessary to accommodate pressure around the top portion of the piston 37, and to also serve as guides for the valve 38 when moving up and down.

The release-valve 38 is, preferably, of the hollow formation, best understood from Fig. 3; that is to say, it is of approximately concavo-convex longitudinal section with an apertured wall 60 near the lower end 56, said wall having serially arranged holes therethrough and inclined relative to the longitudinal axis of the valve 38 to define ports 61 affording flow-communication from the upper side thereof to the correspondingly spaced apertures 57 in the transverse wall 41, of the casing component 21. It is to be also observed that, in addition to the flared lower end 56, the release-valve 38 is provided with an axially-spaced or upper differential flare 62, for seating-engagement on the beveled shoulder 59, in the valve component 21, when said valve is in the lower or closed position of Fig. 2.

From the above explanation of the structural features of the combination differential-piston 37 and double-seated release valve 38, it will be readily understood by those conversant with the art that, when the engine throttle is opened, steam pressure from the chest 10 enters the device 19 by way of the pipe 36 and elbow 35, with flow into the fluted portion 58 of the casing component 21 and flaring upper part of the seated release-valve 38; and by passage through the inclined ports 61 and apertures 57 will exert pressure in the hollow section 42 of the piston 37, whereby the latter is forced away from abutment with the wall 41, or downwardly, as shown in Fig. 2. This downward movement of the piston 37 is resisted by steam, admitted through a rectangular port 63 and pipe connection 64, Fig. 1, from a separate source, preferably the locomotive boiler, with flow by way of the circumferential groove 47 into the differential area between the bore 46 and the flare 45, but such pressure does not move the piston 37 upward until the steam chest pressure has been lowered down to a small amount, preferably from ten to twenty pounds gage pressure, depending somewhat on the friction of the moving parts and closing of the locomotive throttle. In the down position of the piston 37, the pipe connections 29, 30 are in flow communication, by way of registering ports 65 in the liner 31 and piston recess 50, with the pipe 26 into the exhaust passage 11, whereby the central differential portion of the admission poppet valves 12 are connected to said exhaust passage; in accordance with the disclosure.

sure of the prior patent hereinbefore referred to. On the other hand, when the drifting-valve piston 37 is in the up position of Fig. 3, boiler steam is being admitted to the pipes 29 and 69 from the port 63 with the ball valve 66 on its lower seat thereby sealing the steam chest open. When the locomotive is under normal operation the piston 37 is in the down position of Fig. 2, the pipe 29 is sealed against boiler steam, by its bevel 44 engaging the seat 45, and said pipe will then be in communication with the auxiliary port 25 and exhaust pipe 26; whereby the differential cavity of the admission valve 74 is connected with the exhaust. Similarly when the locomotive throttle is normally open steam chest pressure admitted under the ball valve 66 by way of a port 10, leading from the steam chest 10, Fig. 1, holds said valve firmly against the upper seat, while no live steam from the boiler is admitted to the pipe 29 inasmuch as the piston 37 is "sealed" or down so that communication between the port 63 and the pipe 29 is thereby sealed.

When the locomotive throttle is closed and the pressure in the steam-chest 10 drops to somewhere between ten and twenty pounds, as aforesaid, the piston 37 is driven upward by the boiler pressure entering from port 63 with flow through groove 47, into the differential area between the bore 46 and the flare 45 in the liner 31. At the same time, upward movement of the piston 37 lifts the release-valve 38, thereby venting the contained steam-chest pressure through the outlet 52 and pipe 53 to the engine cylinder exhaust passage 11, as readily understandable from Figs. 1 and 2. When the piston 37 is in the up-position, shown by Fig. 3, it will also be observed that the port 63, connects with the respective passages 28 and associated pipes 29, 30, whereby boiler pressure steam is conducted to the admission-poppet valves 12. Such boiler pressure steam is also admitted from the respective pipes 29, 30, by way of a branch 69, to the associated ball check-valve 66 and thereby forces the latter to its lower seat 70, thus closing the passage 71 from the steam-chest 10 by way of the port 10'. This boiler pressure steam being now admitted to the exhaust pilot-valve 15 may do either one of two things, depending on the position of the main locomotive reverse gear, not shown, but well known to those conversant with the art, or on reference to the previously mentioned patent. If the reverse gear lever be left in forward running position while the locomotive is "drifting," the pilot-valve 15 will continue to operate in synchronism with the main or cylinder piston 12, Fig. 1, and thereby deliver steam pulsations to the exhaust-poppet piston 73, which means that the exhaust poppet valve 14 will always be closed whenever the cylinder piston 72 moves away from said poppet valve 14, whereby smoke and exhaust gases are effectively prevented from following said cylinder piston. Should the locomotive reverse lever be placed on dead center while "drifting," which is the preferable position, the exhaust pilot-valve 15 will not receive any impulse from the operating cam 18 and said pilot-valve will remain closed, thus admitting boiler pressure steam continuously on top of the poppet piston 73 and thereby hold the exhaust-poppet valve 14 closed. With the pilot valve 15 controlled by the valve gear as stated, the pressure admission to the top of the differential valve 73 will be intermittent due to the aforesaid action of the pilot valve; but there is no pressure tending to raise said differential valve

because the ball-check 66, under these conditions, will be on its bottom seat, which seals the passage 71 from the steam chest 10 and also seals the passage to the differential cavity in the differential valve. Furthermore, there is no pressure acting on the bottom of differential valve 73 because the steam underneath it is connected to the exhaust passage 11 at all times. It will be further seen that boiler pressure steam being also admitted to the differential or central portion 74 of the piston 75 of the admission-poppet valves 12 as indicated by the arrows at the right hand of Fig. 1, the latter will be held in the upward or open position; and, even though the admission pilot-valve 13 continues to receive impulses from the associated cam 18, the steam-chest 10 having been vented to the exhaust passage 11 through the release-valve 38, as before explained, there will be no steam-chest pressure available to act downwardly on the admission-poppet valve pistons 75. Incidentally, it is to be here remarked that complete venting of the steam-chest 11 does not actually take place so that when the admission valve piston 75 is held up or open there remains a sufficiency of steam in said chest for circulation through the cylinder 9 and associated parts, as readily understandable on an examination of the right-hand portion of Fig. 1, to overcome frictional resistance of the 30 relatively movable parts when the locomotive is "drifting."

The just explained operative conditions continue as long as the locomotive throttle remains closed, and any slight amount of leakage from 35 said throttle-valve is vented through the release-valve 38, thereby preventing pressure from building up in the steam-chest 10 and causing the admission-poppet valves 12 to assume any position other than determined by the drifting control device 19.

On the other hand, when the locomotive throttle is opened, steam entering the chest 10 at first tends to escape through the release-valve 38 to the exhaust passage 11, but the exhaust outlet 52 and pipe connection 53 to said passage are purposely made considerably smaller than the steam-chest connection 36, so that a choke occurs, whereby the large volume of steam coming from the main throttle "almost" instantly forces the control-valve piston 37 down and closes the release-valve 38. The release-valve 38 being hollow, as hereinbefore explained, the steam coming from the chest 10 through the pipe 36 and union-elbow 35 passes 50 through said hollow by way of the inclined ports 61 and apertures 57 and exerts its pressure on the piston 37, to hold said piston down firmly to the seat flare 45 in the liner 31, as clearly shown in Fig. 2; and, in this position, it will be 55 also evident that the boiler pressure steam-flow from the rectangular port 63 entering the circumferential groove 47 will be trapped therein in opposition to the steam chest pressure, while the outlets 25, 52 are again open by way of the connections 26, 53, respectively, to the exhaust 11. At the same time, exhausting of steam from the flow pipes 29, 30 and the admission of steam-chest pressure to the exhaust pilot-valve 15, by way of the passage 68, causes the ball check-valve 66 to be forced upward against the seat 67 and thereby prevents steam-chest pressure passing from said passage 68 into the branch 69 and flow pipes 29, 30.

From the foregoing it is considered the merits and advantages of the disclosed invention will

be clearly apparent without further elaboration herein; also that the explained embodiment thereof fully justifies the objects set forth in the prefatory paragraphs of this specification. Furthermore while there has been particularly set forth what is deemed to be a preferred combination and arrangement of parts for the attainment of the referred to objects, this invention is not limited thereto as there might, obviously, be changes made in the form, construction and assembly of the constituent elements as well as their modus operandi, without departing from the spirit of said invention as comprehended within the scope of the following claims.

Having thus described my invention, I claim:

1. A control device for steam locomotive cylinders having admission and exhaust valves; conduit means included in the locomotive throttling system for supply of steam chest pressure to the device; conduit means for supply of steam, from an independent source and at a different pressure to the control device; means including a differential piston and a coactive relief valve; and associated means operative by the difference in pressure between said supplies of steam to hold the cylinder exhaust valve closed during "drifting" of the locomotive.

2. In a locomotive engine having driving cylinder, steam chest and exhaust provisions, poppet valves for individual admission and exhaust of steam to and from both ends of the cylinder, and associated pilot means controlling opening and closing of said poppet valves; the combination of a drifting control device including a differential-piston and an aligned release valve, flow means for conducting steam chest pressure to the control device to force the differential piston in one direction, means affording flow connection from another source of similar pressure steam to the device for effecting reverse movement of the differential piston and opening of the release-valve with simultaneous holding of the cylinder admission poppet valves open, and means for diverting pressure from the flow connection aforesaid to the exhaust pilot means for holding the associated poppet valve closed during movement of the engine cylinder piston away from said poppet valve when the locomotive is drifting.

3. In a locomotive engine having driving cylinder, steam chest and exhaust provisions, poppet valves for individual admission and exhaust of steam to and from both ends of the cylinder, and associated pilot valves controlling opening and closing of the respective poppet valves; the combination of a drifting control device including a differential-piston and an aligned coactive double-seating release-valve; means for conducting flow of steam chest pressure to the control device to force the differential-piston in one direction, means for supplying pressure from another source of steam to the control device for opposingly moving the differential-piston with opening of the release-valve; means for effecting concurrent closure of the cylinder exhaust poppet valve, said means comprising a connection from the second mentioned source of steam pressure with an associated check means, operative to divert such steam pressure to the top of the exhaust poppet valve, whereby the latter is effectively held closed during drifting of the locomotive.

4. In a locomotive engine having driving cylinder, steam chest and exhaust provisions,

poppet valves for individual admission and exhaust of steam to and from both ends of the cylinder, and associated pilot valves controlling opening and closing of the respective poppet valves; the combination of a drifting control device including a differential-piston and a coactive double-seating release-valve; means for conducting flow of steam chest pressure to the control device to force the differential-piston in one direction; means providing outlet connection from the control device to the cylinder exhaust; means for conducting pressure steam from another source of supply to the control device for opposingly moving the differential-piston and concurrently opening the release-valve; and a connection, from the second mentioned source of steam pressure supply, including a check valve operative to concurrently divert pressure from said supply, to the top of the exhaust poppet valve, for effectively holding said poppet valve closed, during movement of the engine cylinder piston away therefrom, when the locomotive is drifting.

5. In a locomotive engine having driving cylinder, steam chest and exhaust provisions, poppet valves for individual admission and exhaust of steam to and from both ends of the cylinder, and associated pilot valves controlling opening and closing of the respective poppet valves; the combination of a drifting control device comprising a differential-piston and aligned double-seating release-valve, a pipe for flow of steam chest pressure to the control device for forcing the differential-piston in one direction; an outlet connection from the control device to the cylinder exhaust; a pipe supplying pressure steam from another source to the control device for opposingly moving the differential-piston with concurrent opening of the release-valve and closure of the cylinder exhaust poppet valve when the steam chest pressure reduces to a low amount; a branch connection from the second mentioned pipe to the exhaust poppet valve; and an associated double-acting check means serving, when in one position to divert flow of pressure steam from said branch connection to the exhaust poppet valve and thereby effectively hold the latter closed.

6. The combination of claim 5, wherein the outlet connection from the control device to the cylinder exhaust is of considerably smaller size than the inlet pipe for admission of the steam chest pressure, said outlet connection creating a choke in the control device effective to seat the release-valve, and concurrently shut off the pressure steam from the second mentioned source of supply.

7. The combination of claim 5, wherein the double-acting check means is in the form of a ball valve coactive with spaced seats, one of said seats having connection with the pressure flow pipe for the second mentioned source of steam supply, and the other seat being in flow communication with the cylinder steam chest.

8. The combination of claim 5, wherein the release-valve is of ported formation to facilitate flow of steam chest pressure to the major area of the differential-piston, and the minor area of said piston is defined by an end reduction of said piston including a circumferential groove.

9. The combination of claim 5, wherein the differential-piston is provided with an annular recess, and the control device has opposed connections to the cylinder admission and exhaust poppet-valves for flow of pressure steam from

the second mentioned source of supply thereto, when the locomotive is drifting, to hold the admission poppet valves open and the exhaust poppet valves closed.

10. The combination of claim 5, wherein the bore of the control device is provided with an inner annular shoulder for limiting the down movement of the differential-piston, and the said device and piston embody means for flow of pressure steam from the second mentioned source of supply through the control device, when said piston is moved away from the shoulder aforesaid.

11. A drifting control device comprising aligned casing components having a cap at one end with means affording flow communication from a source of pressure fluid, an outlet from said device to exhaust, means in the device defining spaced seats with a series of apertures through one of said seats, a hollow release valve embodying portions for joint coaction with said seats and an axial stem slidable through a complementary orifice in the adjoining seat, a wall across the release valve having a series of ports therethrough in correspondence with the seat apertures, flow connections to the device affording communication from the source of pressure fluid, a differential-piston movable in the device under the influence of motive-fluid supplied from a separate source of pressure, and said piston also serving to open the release valve for venting of the pressure fluid acting thereon.

12. A drifting control device comprising vertically-aligned and detachably connected upper and lower casing components having a cap at the top and a closure wall at the bottom, means affording flow communication through the cap from a source of pressure fluid, an outlet from the upper component to exhaust, means in said upper component defining vertically-spaced seats, an annular series of apertures through the lower seat, a hollow release-valve embodying portions for coaction with said seats and an axial stem slidable through a complementary bore in the lower seat of the upper casing, a wall across the release-valve having a series of ports in correspondence with the lower seat apertures, opposed connections to the lower casing component affording flow communication from the source of pressure fluid aforesaid, an outlet connection from said lower casing component to exhaust, a differential-piston movable in the bore of the lower casing component under the

influence of motive-fluid supplied from another source of pressure, and said piston also serving to lift the poppet release-valve for venting of the pressure acting thereon.

13. A drifting control device as defined in claim 12, wherein the upper casing component embodies a transverse wall with the central part shaped to define a bevel seat, said seat having a surrounding series of apertures therethrough, the upper portion of the bore of said component being longitudinally fluted to afford guidance for the release-valve, a beveled shoulder adjoining the inner ends of the fluting to provide the upper vertically-spaced seat, and a lateral branch intermediate said seats affords connection to exhaust.

14. A drifting control device as defined in claim 12, wherein the hollow release-valve is of approximately concavo-convex longitudinal section, spaced flares circumferentially around said release-valve coact with the upper casing component seats, a transverse wall adjoins the inner end of the release valve, said wall having a central guide stem extending outwards therefrom, and a series of ports through said wall, said ports being circumferentially-spaced around the wall and inclined relative to the longitudinal axis of the valve.

15. A drifting control device as defined in claim 12, wherein the lower casing component embodies diametrically-opposed lateral branches for pressure flow-connections and an outlet in the bottom wall for exhaust, a rectangular port in the casing component wall serves for connection to another source of in-flow pressure, an anti-friction liner in the bore of said component, and said lower casing component includes a flange whereby the control device is attachable to stationary structure.

16. A drifting control device as defined in claim 12, wherein the differential-piston comprises a hollow-section to define the major effective area and a diametrically-reduced and relatively shorter solid extension, with an intervening circumferential bevel defining a minor effective area, an axial bore in said solid extension, a circumferential groove around the solid section, an inclined duct provides drain connection from said groove to the inner end of the solid section axial bore, and a substantial recess surrounds the solid extension.

LLOYD B. JONES.
